[57] CLAIM

The ornamental design for a wall mounted newspaper holder, as shown and described.

DESCRIPTION

FIG. 1 is a top plan view of a wall mounted newspaper holder showing my new design;

FIG. 2 is a front elevational view thereof;

FIG. 3 is a side elevational view taken from the right of FIG. 2, the side opposite being a mirror image thereof;

FIG. 4 is a bottom plan view thereof; and

FIG. 5 is a sectional view taken on line 5—5 of FIG. 2. The rear is flat and unornamented.

FIG. 1

FIG. 2

FIG. 3

FIG. 4

FIG. 5
